UNITED STATES PATENT OFFICE.

WILLIAM HENRY CHENERY, OF MONTREAL, QUEBEC, CANADA.

DETACHABLE FOOTWEAR-TREAD.

1,399,542.

Specification of Letters Patent.

Patented Dec. 6, 1921.

Application filed October 9, 1920. Serial No. 415,890.

To all whom it may concern:

Be it known that I, WILLIAM HENRY CHENERY, residing at 118 Villeneuve street, in the city and District of Montreal, in the 5 Province of Quebec, in the Dominion of Canada, have invented new and useful Detachable Footwear-Treads, of which the following is the specification.

The invention relates to detachable heels 10 and soles as described in the present specification and illustrated in the accompanying drawings that form part of the same.

The invention consists essentially of the 15 novel formation and arrangement of plates and catches whereby the strain on the fastening tends toward more security in the attachment.

The objects of the invention are to economize in regard to the wear and tear of the 20 tread portions of footwear; to furnish a heel which can be readily changed and interchanged by the person wearing the shoes; to insure cheapness in the construction of the fastener parts so that the heel may be 25 sold at a reasonable price to the consumer; to facilitate the manufacture of shoe parts, and generally to provide a reliable, durable and efficient heel.

In the drawings, Figure 1 is a longitudinal 30 sectional view of a lady's shoe showing the fastening parts.

Fig. 2 is a plan view of the sole and heel showing the inner plates.

Fig. 3 is a perspective detail of the 35 detachable heel.

Fig. 4 is a perspective detail of the detachable sole.

Fig. 5 is a longitudinal sectional view 40 showing a man's shoe.

Fig. 6 is a perspective detail of the inner heel plate.

Fig. 7 is a perspective detail of the spring locking bar.

Like numerals of reference indicate corresponding parts in each figure.

Referring to the drawings, the fastening device is shown as formed of the inner plate 1 for detachable heel purposes and outer plate 2, while for the sole it is formed of the 50 inner plate 3 and outer plate 4.

The inner plate 1 is secured to the heel 5 by the screws 6 and in the said heel 5 the inclined central bar channel 7 extends from adjacent to the back of the heel to the front 55 wall of said heel where the cut of the chan-

nel is at its deepest. At each side of the channel 7 intermediate of the distance to the edge of the heel the recesses 8 and 9 are made from the bottom of the heel 5. The plate 1 is cut out to form the slots 10 and 11 60 over the recesses 8 and 9 respectively and the slot 12 over the channel toward the front of the heel 5.

The spring locking bar 13 is riveted to the plate 1 on the inner side and is formed with 65 the offset catch 14, which partially fills in the slot 12 in its normal position. The bar 13 is upwardly turned at the end 15 and fits neatly flush with the heel front wall 70 in the opening to the channel 7.

The outer plate 2 of the fastening is 75 formed with the hook catches 16, 17, and 18, and the barbs 19, 20, and 21. The hooks 16 and 17 engage the plate 1 at the front edges of the slots 10 and 11, and the hook 18 80 at the front end of the slot 12, but the spring catch must first be depressed automatically by hook 18 to enter the slot 12, though after it is hooked the said spring catch falls in behind the hook 18 and locks it and in consequence the other hooks 16 and 17 are 85 locked.

The plate 2 is stamped out with the recesses 10, 11, and 12 as explained, and also with the barb-shape projections 22, 23 and 24. These barbs are forced into the leather tread 25 and hold the plate 2 firmly thereto without the necessity of other fasteners.

The detachable sole 26 is fitted on in similar fashion, the outer plate 4 having the 90 forwardly projecting hooks 27, 28, and 29 and the barbs 30, the inner plate 3 being stamped out with the hook slots 31, 32 and 33. The middle sole 34 is a permanent part 95 of the shoe and is channeled at 35 in front of the shank 36, the slot 33 leading into the channel 35, when the plate 3 is attached to the permanent sole 34 by the stamped out barb fasteners 36 or in any other suitable manner.

The spring locking bar 37 is riveted to the plate 3 and extends along the channel 35. The offset 38 in said bar 37 springs through the slot 33 and forms a catch behind the hook 29 of the plate 4.

The plate 4 is secured to the tread 26 by the barbs 30, and is preferably of leather, likewise the heel tread, though it must be understood that they may be of any suitable material and further that the claim 110

following sets forth the novel features of the construction as it may develop from time to time in its commercial use.

What I claim is:

- 5 In detachable footwear treads, a detachable member formed of a metal plate and the tread proper, said metal plate being formed with barbs projecting into said tread proper and hooks, a permanent member comprising an upper portion and a plate, both being provided with registering holes said

latter plate having barbs projecting into the upper portion, said hooks of the first named plate being constructed and arranged to pass into said holes and engage the second plate, 15 and a locking tongue having an offset to enter one of said holes and in the rear of a hook to lock the same and thereby lock the plates.

Signed at Montreal, Quebec, Canada, this 20
4th day of October, 1920.

WILLIAM HENRY CHENERY.
